UNITED STATES PATENT OFFICE

LESTER H. MILES, OF LOS ANGELES, CALIFORNIA

APPARATUS FOR ELEVATING FLUID

Application filed March 7, 1927. Serial No. 173,230.

This invention relates to an apparatus for elevating fluid.

The general object of my invention is to provide means by which oil in a well may be brought to the surface when the gas pressure in the well is insufficient to cause the well to flow.

Another object of this invention is to provide means which will increase the flow of oil wells in which the gas pressure is so weak that the oil barely flows, and wherein means is employed for lifting the oil in a well to the surface without the application of the customary pump.

Another object of the invention is to provide a novel apparatus including a plurality of stages or lifts for causing removal of oil from wells.

Other objects of this invention will be apparent from the following description taken in connection with the accompanying drawings wherein:

Fig. 1 is a vertical section through an oil well showing one embodiment of my invention placed therein.

Fig. 2 is an enlarged vertical section through a plurality of the stages.

Fig. 3 is an enlarged vertical section through the lower end of one of the conductor tubes showing the check valve mechanism therein.

Fig. 4 is a section taken on line 4—4 of Fig. 3, and

Fig. 5 is a detail section of the overload valve applied to the casing head gas outlet.

Referring to the drawings by reference characters I have shown my invention as embodied in a device comprising a plurality of stages 10 supported by a collar 11 on a casing head 12. Intermediate the length of the uppermost stage I provide oil outlet pipes 13. The stages 10 may extend as far above the casing head 12 as desirable. The stages 10 are surrounded by a casing 14 supported at its upper end in the casing head 12. A gas outlet pipe 15 communicates with the space between the stages 10 and the casing 14. The flow of gas from the casing is preferably controlled by automatic release valves 16 more clearly shown in detail in Fig. 5.

Each stage 10 comprises a cup shaped member including a cylindrical side wall 17 having the lower end closed by a bottom or partition 18 to which a conductor tube 19 is secured. This tube extends an equal distance 55 on each side of the partition 18. Adjacent the lower and upper edges of the stages I provide external threads as at 20 and 21.

The conductor tube 19 is preferably provided at its lower end with a check valve 22. 60 The body of the check valve may be secured to the tube 19 by screw threaded engagement therewith as shown in the drawings or in any other suitable manner. The check valve 22 includes a ball 23 adapted to normally rest 65 in a seat 24. For preventing extensive upward movement of the valve ball 23 I provide bars 26 arranged across the tube 19 at right angles to one another and secured to the tube. 70

When assembling the stages 10 for use each stage is preferably connected to and drawn into tight engagement with each preceding stage by a stage coupling 27. To prevent leakage I may provide a packing element 28 75 of rubber or other material between the top edge of one stage and the bottom of the preceding stage. The lowermost conductor 19 may be provided if desired with a funnel shaped inlet 29 which will act to guide the 80 fluid into the first stage.

As shown in Fig. 5 of the drawing the release valve 16 for controlling the gas pressure in the casing comprises a housing 30, having a screw threaded entrance bore 31 85 communicating with a bore 32 by means of a smaller bore 33. The end of the bore 33 adjacent the bore 32 is chamfered to form a valve seat for a ball valve 34, which is normally held in the valve seat by a compression 90 spring 35. The tension of spring 35 may be adjusted by means of a screw threaded plug 36, engaging similar threads in the bore 32, and held against rotation by means of a lock nut 37, and communicating from one side of 95 the bore 32 to a screw threaded outlet bore 38 is a bore 39.

The operation of my device is as follows: The oil and gas enter through the inlet 29 and pass into the lowermost stage. The oil 100

- and gas rise in the stages until the same level within and without the stages is reached. From this level the gas passes up into the next stage wherever it may be located and 5 this gas carries with it some of the oil. This oil falls onto the partition 18 and the accumulation of oil soon rises above the bottom of the valve seat 22. The gas pressure then increases in the stage under discussion and the 10 gas passes up the conductor tube 19, past the ball 23. This gas carries some of the oil with it and this oil falls upon the next higher partition and the process is repeated until the oil passes out through the pipe 13.
- 15 As the gas pressure accumulates in one of the stages and forces the oil upward through a conductor 19 to the next highest stage, the valve 22 in the conductor 19 through which the oil has entered said stage, will prevent 20 the oil in the stage from being forced back down again.

From the foregoing description it will be apparent that I have provided a novel, simple and efficient means for lifting oil in a well 25 to the surface.

What I claim is:

1. In a well, the combination of a casing, a casing head, means associated with said head for lifting the oil in the well by means of the 30 contained gas, said means including a plurality of stages connected together, each of said stages comprising a tubular member provided with a transverse partition, a conductor tube secured to said partition and extending 35 downwardly into the stage and upwardly into the next adjacent stage, a one-way valve at the end of said conductor tube and means on each of said stages for securing said stages together.
- 40 2. In a well, the combination of a casing, a casing head, means associated with said head for lifting the oil in the well by means of the contained gas, said means including a plurality of stages connected together, each 45 of said stages comprising a tubular member provided with a partition, a conductor tube extending downwardly into the stage and upwardly into the next adjacent stage, said tubes being out of alignment with each other, 50 a one-way valve associated with said conductor tube and means on each of said stages for securing said stages together, and means below the highest oil level in said fluid lift 55 for removing the oil raised by said stages.
- 60 3. For use in an oil well, means for lifting the oil therein through the medium of the gases contained in the oil, said means comprising a casing, a series of superposed stages in said casing for receiving and holding accumulated oil and gas, a conductor tube in each stage and extending into the next adjacent stage, the entrance to each tube being 65 provided with a valve and being located at a lower level than the exit of the next adja-

cent tube, the adjacent conductor tubes being out of alignment.

In testimony whereof, I hereunto affix my signature.

LESTER H. MILES.
